United States Patent Office

Des. 212,688
Patented Nov. 12, 1968

212,688

CAR WASH BUILDING

Richard J. Shelstad, Mequon, Wis., assignor to Edick
Laboratories, Inc., Milwaukee, Wis., a corporation of
Wisconsin

Filed Feb. 29, 1968, Ser. No. 10,787

Term of patent 14 years

(Cl. D13—1)

Fig. 1

Fig. 2

Fig. 3

FIG. 1 is a perspective view of a car wash building showing my new design;

FIG. 2 is a front elevation view;

FIG. 3 is a rear elevation view;

FIG. 4 is a side elevation view, and

FIG. 5 is a top plan view.

The left side of the building is unornamented.

I claim:

The ornamental design for a car wash building, substantially as shown and described.
